(57) **CLAIM**

The ornamental design for an adjustable cap for lumber, as shown and described.

DESCRIPTION

1. Adjustable cap for lumber

1.1: Perspective

1.2: Perspective

1.3: Front

1.4: Back

1.5: Top

1.6: Bottom

1.7: Right

1.8: Left

(Continued)

1. The broken lines in the drawings form no part of the claimed design.

1 Claim, 8 Drawing Sheets
